UNITED STATES PATENT OFFICE

JOHN C. SCHUMACHER, OF DAYTON, OHIO, ASSIGNOR TO THE DAYTON MFG. COMPANY,
OF DAYTON, OHIO, A CORPORATION OF OHIO

DOUBLE-PAN HOPPER AND VALVE

Application filed October 28, 1929. Serial No. 402,844.

This invention relates to improvements in hoppers and water valves connected with water closets, and more particularly relates to water closets used in connection with railway cars and the like. While it is particularly adapted for use in connection with railway cars it may be used in other places.

It is particularly an object of this invention to provide, in connection with the hopper, two flush pans, a lower and an upper one, with mechanism for operating these pans in connection with a side valve, for admission of water to the hopper.

It is a further object of this invention to provide means for first elevating the lower pan, which is normally open, and thereafter raise the upper pan, which is normally closed, and at the same time admit water to the hopper for the purpose of flushing it. All of these operations are performed by one single operating lever, which acts first to close the lower hopper, open the upper hopper and admit water thereto.

It is also an object of this invention to provide a side valve mechanism to which are attached the operating means for shifting the flush pans and opening and closing the valve, and means cooperating with the operating means for holding all the flush pans open so that the whole hopper may be flushed and drained at one time.

It is a further object of this invention to provide, in a double flush pan hopper having a side valve, an interconnecting mechanism between the valve and the flush pans for operating the pans successively in the flushing of the hopper and for providing a water seal in the upper pan after the hopper has been flushed and the pans returned to normal position.

For the purpose of illustration there is shown in the accompanying drawings a preferred embodiment of this invention.

Referring to the drawings:

Figure 1 is a side elevation of the hopper with the pan and valve controlling apparatus attached thereto.

Figure 2 is a top plan view of the apparatus as shown in Figure 1.

Figure 3 is a vertical longitudinal sec-

tion through the valve casing and the valve mechanism inclosed therein.

Figure 4 is a vertical cross section showing the valve shaft and the means for operating the valve stem. 55

Figure 5 is a front end view of the valve casing.

Figure 6 is a side elevation of the hopper and its associated mechanism, with the lower part of the hopper in section showing the pans in their normal positions, the upper pan being closed and the lower pan being open.

Figure 7 is a view similar to Figure 6 but showing the lower pan closed and the upper 65 pan open.

Figure 8 is a view similar to Figures 6 and 7 showing the positions of the pans immediately after the hopper has been flushed, but with the valve partly open for the purpose of admitting water to the hopper after 70 the upper pan has been closed.

Figure 9 is a view similar to Figures 6, 7 and 8, but showing the pans both in open 75 position and locked in that position.

Figure 10 is a section through the rear end of the valve casing showing the by-pass.

In Figure 1 there is shown the side elevation of applicant's invention, as applied to a hopper used in connection with water closets 80 found in connection with railroad cars. The hopper is indicated by the numeral 1. This hopper is provided with the usual seats, as shown in the upper part thereof, which form no part of this invention.

The lower part of the hopper is contracted, and is provided with two closures therefor, one above the other. These closures are termed pans, the upper one of which is indicated by the numeral 2, and is pivoted to the rear wall of the hopper at a point indicated by the numeral 3, which has a shaft and extends beyond the walls of the hopper.

On one end of this shaft is a weight 4 which 95 tends to keep the hopper closed, or assist in closing it when the operating lever is released. On the opposite end of this shaft from the weight is a crank arm 5. This crank arm has a hollow stub shaft on one end, indicated by 100

the numeral 6, adapted to receive a square end of the shaft 3.

The lower pan, which is normally open, is indicated by the numeral 7, and is pivotally mounted to a suitable bracket on the rear end of the rear wall of the hopper. The point of pivot is a shaft indicated by the numeral 8. This pan is pivoted by means of a shaft which has on one end a weight 9, very similar to the weight 4, and tends to hold this pan normally open, as shown in Figure 1. On the other end of this shaft from the weight 9 there is mounted a crank arm 10, which has extending therefrom a stub shaft 11 with a socket therein to receive the end of the shaft 8.

As shown in the figures, there is located above the hopper to some suitable support, as for instance, the rear side wall valve casing 12. This valve casing is shown in section in Figures 3 and 4. The inlet to this casing is indicated by the numeral 13, while the outlet is indicated by the numeral 14. The inlet is connected to some suitable source of water, while the outlet is connected by a pipe to the upper part of the hopper. This pipe is indicated by the numeral 13'.

In the water passageway between the inlet and the outlet there is a valve seat 15. This valve seat is adapted to receive a valve 16 for the purpose of closing the passageway to prevent the flow of water from the inlet to the outlet. On one side of this valve is a hollow valve stem 17, which fits within an opening in a hollow plug 18, which is screw threaded into an aperture in the front wall of the casing. Within the plug 18 and also fitting within the hollow stem 17 is a spring 19, the purpose of which is to hold the valve 16 normally seated in the seat 15.

Extending from the valve, in a direction opposite to the valve stem 17 is an inner valve stem 20, which is held in engagement with the valve and the outer valve stem by means of a screw 21. These parts may be made of any suitable material. The valve preferably is made of some soft yielding material that will adapt itself to the shape of the valve seat.

The inner end of the valve stem 20 has a socket therein 22, which receives the reduced end of the operating stem 23. The end of the operating stem 23 remote from the valve stem 20 is reduced. The part of the valve casing in which the operating stem 23 is located is cylindrical in form and is adapted to be used as a dash pot cavity 24. The end of this dash pot cavity remote from the valve seat is open. For the purpose of closing this opening there is provided a cap 25, which has therein a hole 26 in which the reduced end of the operating stem fits and moves. This reduced end of the operating stem that fits into hole 26 is indicated by the numeral 27.

For the purpose of forming a dash pot structure there is provided in the dash pot cavity 24 a dash pot valve 28. This valve

is constructed as valves of this class are, and has for its object to retard the movement of the valve stem 23 back and forth, and prevent any rattling or sudden or jerking movement of the valve.

For the purpose of aiding the dash pot in control of the valve and retard its movement, there is a by-pass 29. This by-pass is shown in Figures 10 and 4. Figure 10 shows the part of the by-pass that enters into the cap 25 which forms a closure for the dash pot. Figure 4 shows the entrance of the by-pass into the casing to the left of the dash pot valve, as shown in Figure 3.

For the purpose of regulating the flow of water through the by-pass there is a valve indicated by the numeral 30. This valve is in the form of a conical point, which is screw threaded in a plug, and for the purpose of adjusting the valve it may be screwed in or out so as to partly close or entirely open the by-pass 29 and thereby regulate the flow of water around the dash pot valve.

Mounted within the casing there is a shaft 31 used for the purpose of operating the valve, and for this purpose has extending therefrom an arm 32, the end of which is circular in shape and fits within a slot or socket 33 in the operating stem, as shown in Figure 3. On the outer square end 34 of this shaft is a lever 35. For the purpose of engaging this shaft the lever has near the center thereof a square socket which fits over a correspondingly shaped end of this shaft. The part of the lever 35 which receives the end of the shaft 31 is enlarged and formed in the shape of a circular boss 36.

On one end of the lever 35 there is a lug 37 which extends downwardly, outwardly and upwardly from the lever. The end of the lever 35 remote from the lug 37 is split, as indicated by the numeral 38. Extending from the split end of the lever 35 to the crank arm 5 is a connecting rod or link 39. This link is connected to the lever 35 by means of a joint connection 40, and is connected to the crank arm 5 by means of a joint connection 41.

Pivottally mounted upon the boss 36 is a hand lever 42. For the purpose of this mounting the lever is provided near its center with an enlarged opening, and is held in position on the boss by means of a screw 43. One end of this lever is adapted to be engaged by the hand, while on the other end there is formed a split 44, to which one end of the link 45 is attached. The link 45 is attached to the lever 42 by means of a joint connection 46 and to the crank arm 10 by means of a joint connection 47.

The link 45 is in two sections, one end of one section fitting within one end of the other section. Between the telescoping ends of these sections is a compression spring 45' which allows a slight elongation of the link 130

so that after the flush pan 7 is raised the lever 42 may be further moved to dump flush pan 2 and open the valve for the admission of water to the hopper. The valve casing and the lever 42 are mounted on the wall of the water closet adjacent the hopper so that a person seated on the hopper may flush it without moving therefrom.

The lever 35 is operated by means of lever 42. As lever 42 is operated to raise the lower pan it will also operate the lever 35 to lower the upper pan, but the lowering of the upper pan takes place after the first pan has been substantially raised to closed position. This operation of the lever 35 by lever 42 is effected by the lever 42 engaging the lug 37 on the end of the lever 35.

For the purpose of locking the lever 35 in such a position that the pan operated thereby is open, there is provided a pin 48. This pin, in the form of a lock pin, is located in a suitable slot in the front end of the casing. The handle for the operation of this pin is indicated by the numeral 49 and moves along and through a slot 50. When this pin is in one position the lever 35 is free to oscillate for the purpose of opening and closing the upper pan, but when the pin 48 is in an outwardly extending position it engages above the lever and locks it so that the pan operated thereby is held open.

When this lever is thus locked both pans are open since the normal position of the lower pan is open. In this position of the pans the hopper may be washed and drained, as the valve is also open when the parts are so locked.

For the purpose of supporting the valve casing there is provided on the rear thereof a valve plate 51. This plate is attached to the casing in any suitable manner by rivets, screws or otherwise. This casing is also mounted on supports, either a studding, upright or wall, by means of screws or bolts 52.

From the foregoing it is obvious that applicant has provided an apparatus for use in connection with water closets on railroad trains, which is easily operated and effective for the purpose for which it is intended. Merely by pressing down a lever 42 the lower pan is first closed, or substantially closed, after which by a continued operation of the same lever the upper pan is opened and the hopper is flushed because of the operation of the valve stem and the consequent opening of the valve.

When the lever 42 is released and the parts permitted to assume their normal positions, the lower pan becomes open due to its weight as well as to the operation of the lever 42, while the upper pan is closed due to its weight and the operation of the lever 42.

But after the upper pan is closed the valve is still sufficiently open to permit a sufficient flow of water into the hopper so that there

is at all times a slight amount of water maintained in the hopper. After this slight flow of water is permitted the valve is finally cut off so that there is no further flow until the lever is again operated for the purpose of flushing the hopper.

I desire to comprehend within my invention such modifications as may be clearly embraced within my claims and the scope of my invention.

Having thus fully described my invention, what I claim is new and desire to secure by Letters Patent, is:

1. In a water closet, a hopper having a water inlet pipe and a pair of pivoted flush pans, one normally closed and the other normally open, and movable means comprising a pair of levers, one operable in the first stages of its movement to close the open pan and on further movement to operate the other lever to open the closed pan and to admit water through the inlet pipe to the hopper.

2. In a water closet, a hopper having a water inlet pipe and a pair of flush pans, one being normally open and the other being normally closed, a casing having a valve and valve shaft therein to control the flow of water through said pipe, a lever on said shaft connected at one end to one of said pans to open and close it, and a second lever connected at one end to the other pan to open and close it and adapted to engage the first lever to operate it, whereby on operation of said second lever the first named pan is substantially closed and thereafter the second named pan is opened and the valve operated to admit water to the hopper.

3. In a water closet, a hopper having a pair of vertically swinging vertically disposed flush pans, means for admitting water to said hopper including a valve and valve shaft, a lever on said shaft connected at one end to one of said pans, a second lever pivoted to the first lever and connected at one end to the other pan and adapted to engage the first lever, whereby on operation of the second lever its pan is raised and thereafter the first lever is operated by the second lever to raise the second lever's flush pan and to operate the valve to flush the hopper.

4. In a water closet, a hopper having a water inlet pipe, a pair of flush pans, one normally closed and the other normally open, means operable to first close the open pan and thereafter open the closed pan and to admit water to the hopper, and means to lock the normally closed pan in open position when said first means is operated to restore the parts to their normal position, whereby all pans are open and the water is flowing through the hopper.

5. In a water closet, a hopper having a water inlet pipe and a pair of flush pans, one normally closed and the other normally

open, a valve and valve shaft to control the flow of water to the hopper, a lever on said shaft connected at one end to said normally closed pan, a second lever pivoted on the first lever and connected at one end to the normally open pan, means on the first lever to be engaged by said second lever, said levers being so constructed that a rotation of the second lever closes the open pan and engages the first lever to rotate it to open the closed pan and rotate the valve shaft to open the valve to flush the hopper, and means to lock the first lever to hold the first pan and valve open when the second pan returns to its normal position.

6. In a water closet, a hopper, an upper normally closed and a lower normally open flush pan, a casing having a valve and a valve operating shaft therein, and a water pipe leading thereto and to the hopper, a lever to operate the valve and the upper flush pan, a second lever connected to the lower flush pan and adapted on operation to rock the first lever, whereby the lower flush pan is first closed and thereafter the upper flush pan and the valve are open, and a sliding catch to engage the first lever to hold it in valve and flush pan open position when the second lever is returned to flush pan open position so that the hopper may be drained and washed out.

7. In a water closet, a hopper having a plurality of compartments, a side casing having water connection with said hopper, a valve and a valve operating shaft in said casing, interconnecting means between said shaft and said compartments whereby on rotation of said shaft the compartments are successively flushed, and means on said casing to engage said interconnecting means so that all the compartments may be flushed at one time.

8. In a water closet, a hopper having a pair of compartments, a valve having a shaft for admitting water to the hopper, a lever having a boss on said shaft and adapted to open one compartment and operate the valve to admit water to the hopper, and a second lever mounted on the boss and adapted to close the other compartment and thereafter operate the other lever for purposes set out.

In testimony whereof, I affix my signature.
JOHN C. SCHUMACHER.
